D8-381.

OR D6-973

EX

UNITED STATES PATENT OFFICE.

OTTO F. FOGELSTRAND, OF KENSINGTON, CONNECTICUT, ASSIGNOR TO HART, BLIVEN & MEAD MANUFACTURING COMPANY, OF SAME PLACE.

DESIGN FOR BRACKET.

Specification forming part of Design No. 6,978, dated November 4, 1873; application filed June 30, 1873.
[Term of Patent 7 years.]

To all whom it may concern:

Be it known that I, OTTO F. FOGELSTRAND, of Kensington, in the county of Hartford and State of Connecticut, have invented and produced a new and original Design for a Bracket, of which the following is a specification:

The nature of my invention is fully represented by the accompanying engraving, to which reference is made.

The brace which supports the right-angled sides of the bracket consists, mainly, of vertical bars and curved braces, each of said bars being a little shorter than the rear one adjoining it, so that the ends of the bars and the braces

form a series of corrugations at the front edge of the brace, as shown. The spaces between the bars and braces may be filled with ornamental work, if desired.

I claim as my invention—

A design for a bracket in which the support for the right-angled sides is composed of vertical bars and curved braces, each of said bars being a little shorter than the rear one adjoining it, all arranged substantially as described.

OTTO F. FOGELSTRAND.
